UNITED STATES PATENT OFFICE.

RUDOLF KEIL, OF NEW YORK, N. Y.

NIPPLE-PROTECTOR.

1,191,516.

Specification of Letters Patent. Patented July 18, 1916.

Application filed May 18, 1916. Serial No. 98,270.

To all whom it may concern:

Be it known that I, RUDOLF KEIL, a citizen of Switzerland, residing at New York city, Bronx county, State of New York, have invented certain new and useful Improvements in Nipple-Protectors, of which the following is a full, clear, and exact description.

This invention relates to improvements in sanitary nipple-protectors, or protectors for articles similar to nipples, such for instance as pacifiers for infants.

The object of my invention is to provide a protective cap or sheath arranged to be slipped over a nipple or a pacifier, when said nipple or pacifier is not in use, thereby keeping the air, dust or disease germs from coming in contact with the article which is placed in the infant's mouth. In other words, my invention is directed to promote a sanitary condition of a nipple or pacifier by protecting the same when not in use, special means being provided to hold the protector in place after it has been slipped over the nipple or pacifier. To still further promote sanitation, I provide the protector with an antiseptic pad designed to aid in keeping the nipple or pacifier in a sanitary condition.

I will now proceed to describe my invention in detail, the essential features of which will be summarized in the appended claims, reference being had to the accompanying drawing, forming part hereof, wherein:

Figure 1 is a side elevation, on an enlarged scale, of a pacifier, having my improved protector applied thereto, the protector being shown in section; Fig. 2 is a bottom plan view, on an enlarged scale, of my improved protector; Fig. 3 is a view similar to Fig. 1 illustrating my improved protector as applied to the nipple of a nursing bottle; and Fig. 4 is an enlarged fragmentary side elevation of the lower end of the protector illustrated in Fig. 3.

In Fig. 1 of the drawing, 1 indicates a common form of a pacifier for infants, said pacifier being provided with the usual mouth guard 2 to prevent the pacifier from being drawn into the infant's mouth.

My improvement consists of a protector 3 arranged to completely cover or envelop the pacifier. The protector 3 consists of a

cylindrical body portion 4 having a closed rounded end 5 and an annular flange 6 at 55 the opposite end, said flange 6 being provided with resilient retaining-fingers or clips 7 to engage the mouth guard 2. Within the cup-shaped end of the protector, I place a pad 9 which is preferably saturated 60 with any desired antiseptic solution that will not leave any undesirable effect upon the nipple of the pacifier.

When the protector is placed over the nipple of the pacifier, as shown in Fig. 1, 65 the nipple will be completely protected from the air, dust, etc. When the protector is pressed home, after it has been placed over the nipple of the pacifier, the clips 7 will engage the mouth guard 2 and prevent 70 the premature removal of the protector.

As an extra precaution, I may place within the rounded end 5, a pad 8 which is also saturated with an antiseptic solution. The protector is preferably made into a rigid 75 structure, and can be formed out of any suitable material, preferably celluloid or vulcanized rubber. The clips 7 are extensions of the annular flange 10 which retains 80 the pad 9 in place.

For use in connection with a nursing-bottle nipple, indicated by 11, Fig. 3, I provide the protector 3 with an annular recess 12 adjacent the open end thereof to receive the expanded portion 13 of the nipple, the open 85 end of the said nipple being stretched over the end of the nursing bottle, a portion of which is indicated by 14. This form of protector is also provided with retaining-fingers or clips 15, adjacent the recessed portion 12, to retain the protector in place. This form of protector is also provided with a rounded closed end 5 containing the pad 8 for the antiseptic solution. Both forms of my protectors are provided with an eye 16 90 for the passage of a ribbon or the like, by means of which the protector can be attached to the infant's neck, to the bottle, or to the pacifier.

Having now described my invention, what 100 I claim and desire to secure by Letters Patent is:

1. A protecting cap or sheath for nipples or the like, consisting of a cylindrical body portion to envelop the nipple, means to retain said body portion in position thereon,

and antiseptic pads carried by said cap or sheath.

2. A sanitary protecting cap or sheath for nipples or the like, comprising a rigid cylindrical body portion having a closed end and adapted to envelop a nipple, resilient retaining-fingers or clips projecting from and integral with the open end of said body

portion, and an antiseptic pad retained within the body portion. 10

Signed at New York city, N. Y., this 17th day of May, 1916.

RUDOLF KEIL.
